Primary Examiner — Darlington Ly(74) *Attorney, Agent, or Firm* — Daryl R. Wright; Greg Carr(57) **CLAIM**

I claim the ornamental design for a bumper for a model vehicle, as shown and described.

DESCRIPTION

FIG. 1 is a top, front, and left side perspective view of a bumper for a model vehicle showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, rear, and right side perspective view thereof; and,

FIG. 9 is a top, front, and left side perspective view thereof as installed to the front of an environmental model vehicle. The broken line showing of an exemplary model vehicle in FIG. 9 is provided for the purpose of illustrating environmental structure. All other broken lines in the drawings illustrate portions of the bumper for a model vehicle. No subject matter depicted in broken lines form part of the claimed design.
